ATTORNEY

UNITED STATES PATENT OFFICE.

CHARLES R. FARGO, OF CHICAGO, ILLINOIS, ASSIGNOR TO WILSON-JONES LOOSE LEAF COMPANY, OF CHICAGO, ILLINOIS, A CORPORATION OF ILLINOIS.

BINDER-LOCKING MECHANISM.

Application filed April 9, 1917. Serial No. 160,635.

To all whom it may concern:

Be it known that I, CHARLES R. FARGO, a citizen of the United States, and a resident of the city of Chicago, in the county of Cook 5 and State of Illinois, have invented certain new and useful Improvements in a Binder-Locking Mechanism; and I do hereby declare that the following is a full, clear, and exact description of the same, reference being had to the accompanying drawings, and to the numerals of reference marked thereon, which form a part of this specification.

This invention relates to an improved form of loose leaf binder equipped with a 15 simple locking mechanism for the impaling posts, so constructed that the impaling posts may be engaged through the binder without necessitating manual actuation of the locking mechanisms and yet with the locking 20 mechanism holding said impaling posts against separation from the binder except by manual release of the locking mechanism.

Other and further important objects of 25 this invention will be evident from the disclosure in the drawings and specification.

The invention (in a preferred form) is illustrated in the drawings and hereinafter more fully described.

On the drawings:

30 Figure 1 is a plan view of a binder embodying the principles of my invention.

Figure 2 is a fragmentary central horizontal section taken through the locking plate of one of the binder cover members.

35 Figure 3 is a sectional detail taken on line 3-3 of Figure 2, with parts in plan view.

Figure 4 is an enlarged fragmentary detail section taken on line 4-4 of Figure 3.

40 Figure 5 is a detail section taken on line 5-5 of Figure 3.

As shown on the drawings:

The reference numeral 1, indicates as a 45 whole the top cover of a loose leaf post binder, which is attached to a binder plate 2, in any suitable manner. Said binder plate 2, as clearly shown in Figures 2 and 3, is tubular, and is closed at each end by plug members 3. An impaling post hole 4, is provided in the top wall of the tubular binder 50 plate 2, and another impaling post hole 5, aligned therewith in the lower wall of the binder plate, there being a pair of such holes 4 and 5, at each end of the binder plate. The impaling posts for projection

through the pairs of registering apertures 55 4 and 5, of the binder, are denoted by the reference numerals 6, and the lower ends thereof, as shown in Figure 2, are threaded in order that the same may be rigidly and fixedly secured in the stationary cover member of the binder.

Secured transversely through the tubular member 2, near each end thereof, are pintle shafts 7, and pivotally mounted between collars 8, disposed on each end thereof, are 60 flat locking levers 9. An aperture 10, is provided at one side in the outer end of each of the flat levers 9, and is slightly larger than the diameter of the impaling posts 6, in order to permit an easy movement of the 65 impaling posts through the aperture when the plane of the aperture is at right angles to the axis of the impaling post. Each of said flat levers 9, is provided with an actuating button 11, secured at one end and which projects through an aperture 12, provided in the top surface of the binder plate 2. Disposed beneath one end of each of the levers 9, is a coiled compression spring 13, seated upon the interior of the tubular binder plate 2, which operates normally to hold 70 said button 11, in its outwardly thrust position, such as shown in Figures 2 and 4, with the lever 9, swung downwardly, so that 75 the lever binds tightly against the impaling post 6.

The operation of the device is thought 80 to be obvious from the description. However, when it is desired to disengage the detachable binder plate 2, and its cover 1, from the impaling posts 6, of the binder, it is only necessary to depress the buttons 11, thereby swinging the flat levers 9, from 85 the full line position shown in Figures 2 and 4, into the full line position shown in Figure 3, or the dotted line position shown in Figure 4, that is, with the plane of the apertures 10, of the respective levers 9, more nearly at right angles to the axes of 90 the impaling posts 6. Due to the fact that the apertures 10, in each of the respective locking levers 9, are only slightly larger than the impaling posts 6, when either one of said levers swings into an inclined position under the stress of its impelling spring 13, as shown in Figure 4, the edges of the aperture 10, bind and grip tightly against 100 the sides of the impaling post 6, to prevent 105

vent separating movement between the binder plate 2, and the impaling posts. In fact, any tendency to separate the binding plate from the impaling posts will only 5 serve to increase the gripping effect of the locking levers upon the impaling posts. However, an insertion movement of the impaling post through the binding plate is readily permitted, that is, referring to 10 Figures 2 and 4, the binding plate 2, may be thrust downwardly upon the impaling posts 6, without the necessity of depressing the actuating buttons 11. This is for the reason that such movement of the binder 15 plate upon the impaling posts will serve to swing the locking levers 9, from their inclined locking position upwardly into release position. Consequently, in placing the detachable binder plate upon the impaling posts to clamp the leaves of the binder plate beneath the binder plate 2, while slidably engaging the same downwardly upon the impaling posts 6, the locking mechanisms will serve to tightly grip 20 the impaling posts from retractive movement with respect thereto.

I am aware that various details of construction may be varied through a wide range without departing from the principles of this invention, and I therefore do not purpose limiting the patent granted otherwise than necessitated by the prior art. 25 I claim as my invention:

1. In a temporary binder, a hollow binder plate having holes in its walls, impaling posts through said holes traversing said binder plate, sheet metal levers each having a hole through which one of said posts goes, 35 pintles for said levers secured in the walls of the binder plate and crossing the same at right angles to the posts, the planes of the sheet metal levers being each parallel to its pintle, and loops struck from the sheet metal of the levers and forming holding means for pivotally securing said levers 40 each to its pintle.

2. In a temporary binder, a hollow binder plate having holes in its walls, an impaling post through said holes traversing said binder plate, a sheet metal lever having a hole through which said post goes, a pintle for said lever secured in the walls of the binder plate and crossing the same at one side of and at right angles to said post and a pivotal mounting connecting said 50 pintle and said lever, the said hole in the lever being at one side of a line through said pivotal mounting along said lever and at right angles to said pintle.

In testimony whereof I have hereunto 55 subscribed my name in the presence of two subscribing witnesses.

CHARLES R. FARGO.
